(57) **CLAIM**

The ornamental design for a combined fishing chair and carrier, as shown and described.

DESCRIPTION

FIG. 1 is a front perspective view of a combined fishing chair and carrier showing my new design;

FIG. 2 is a rear elevational view of the combined fishing chair and carrier.

FIG. 3 is a right side elevational view of the combined fishing chair and carrier.

FIG. 4 is a front elevational view of the combined fishing chair and carrier.

FIG. 5 is a top view of the combined fishing chair and carrier.

FIG. 6 is a bottom view of the combined fishing chair and carrier; and,

FIG. 7 is a left elevational view of the combined fishing chair and carrier.

The broken line showing a cooler is for the purpose of illustrations and forms no part of the claimed design.
